US00D775725S

(12) **United States Design Patent** (10) **Patent No.:** **US D775,725 S**
(45) **Date of Patent:** **** Jan. 3, 2017**

(54) **DUAL CHAMBER PROSTHESIS INSERTION DEVICE**

(71) Applicant: **Robert G. Anderson**, Aledo, TX (US)

(72) Inventor: **Robert G. Anderson**, Aledo, TX (US)

(**) Term: **15 Years**

(21) Appl. No.: **29/564,166**

(22) Filed: **May 11, 2016**

(51) LOC (10) Cl. **24-02**

(52) U.S. Cl.

USPC **D24/115**

(58) **Field of Classification Search**

USPC D24/115, 118, 127, 155; 604/92, 108, 604/317, 327, 339, 403, 408, 410, 415; 383/22, 383/23, 35; D9/696, 707, 709; 206/219; 606/1

(57) **CLAIM**

The ornamental design for a dual chamber prosthesis insertion device, as shown and described.

DESCRIPTION

FIG. 1 is a top, side perspective view of a dual chamber prosthesis insertion device;

FIG. 2 is a top view thereof;

FIG. 3 is a bottom view thereof;

FIG. 4 is a right side view thereof;

FIG. 5 is a left side view thereof;

FIG. 6 is a first end view thereof;

FIG. 7 is a second end view thereof; and,

FIG. 8 is a top view thereof with the flaps in an open position.

1 Claim, 5 Drawing Sheets
